(57) **CLAIM**

The ornamental design for a bottle, as shown and described.

DESCRIPTION

FIG. 1 is a top, front, right side perspective view of the bottle, showing the new design;

FIG. 2 is a front elevational view of the bottle;

FIG. 3 is a rear elevational view of the bottle;

FIG. 4 is a side elevational view of the bottle;

FIG. 5 is another side elevational view of the bottle;

FIG. 6 is a top plan view of the bottle; and,

FIG. 7 is a bottom plan view of the bottle.

The broken lines in the drawings showing various elements of the bottle are included for the purpose of illustrating environmental structure and form no part of the claimed design.
